UNITED STATES PATENT OFFICE

AMMON T. SEXE, OF HILLS, MINNESOTA

RERAILING DEVICE

Application filed September 3, 1930. Serial No. 479,549.

This invention relates to devices whereby derailed cars may be guided back upon the rails of the track and particularly to devices of this character having certain improved features whereby the rerailing is effected and which is so constructed that it may be readily applied to the rails of a track and clamped thereon on either side of the track so as to guide the wheels thereon.

10 Other objects will appear in the course of the following description.

My invention is illustrated in the accompanying drawings, wherein:—

Figure 1 is a top plan view of my rerailing device, one of the guideways being partly broken away;

Figure 2 is a longitudinal elevation of the element B;

Figure 3 is a longitudinal elevation of the element A;

Figure 4 is an elevation of the element A looking from the inside of the track toward the element;

Figure 5 is an end elevation of the element A;

Figure 6 is an opposite end elevation of the element A;

Figure 7 is a section on the line 7—7 of Figure 1.

30 It will be seen from these drawings that my rerailer consists of two wheel guiding elements, one designated A and one B. These elements A and B are alike but reversed with relation to each other. Each element consists of a hollow casting, though I do not wish to be limited to this, the casting being formed to provide an upper longitudinally extending inner slightly bowed upper surface 10 which extends the entire length of the casting or element, the bowed portion being slightly flattened midway of the ends of the element. Forming a vertical wall to this flattened portion 11 is a shoulder 12 defining an upper surface 13 which is bowed and gradually merges into the surface 10 at the ends of the portion 13. Extending approximately from one end of the casting inward and toward the middle thereof is a shoulder 14 which at its middle is approximately coincident with the shoulder 12. The casting is

also formed to provide an upwardly extending face or shoulder 15 which starts from one end of the casting to the middle thereof and is relatively straight for nearly its entire length.

55 The shoulder 14 in front of this shoulder 15 is rounded inward as at 16, this bevel or rounded surface gradually increasing in its angle as at 17 as it nears the end of the shoulder 15. The extremity of the shoulder 15 is 60 rounded off or beveled off as at 18. The shoulder defines an upper surface 19 which slants upward toward the middle of the block and is cut off or terminates at 20 in a vertical shoulder. Adjacent the extremities of the 65 casting, the upper face of the casting is cut down to form ledges 21, one at each end of the casting and the extremities of the casting are formed with sockets 22. Associated with the elements or castings 10 are the guideways 70 designated generally 23, each of these guideways being wider at its outer end than at its inner end and the inner end of each guideway being slightly rounded as at 24. The upper face of each guideway is formed with guide channels 25 which converge toward the upper end or small end of each guideway.

Below the upper or small end of each guideway, there is a cross piece 26 which is formed with dowels 27 somewhat smaller than 80 the sockets 22 but adapted to be engaged therewith. Inasmuch as the sockets are smaller than the dowels, it follows that the guideways 23 may be shifted into different angular relations to the castings 10 and yet 85 maintain connection therewith. Thus either edge of a guideway may be disposed against a rail X or Y. The castings are of such length as to rest upon the ties and the guideways are beveled at their lower ends so as to come 90 close to the roadway or ballast of the road so as to permit the car wheels to be guided up the guideways on to the elements A and B and thence on to the rails.

95 The elements A and B are clamped in place upon the rails X and Y by means of the clamps 28, each clamp having a head 29 at one end and a higher head 30 at the opposite end. This higher head is placed exteriorly 100 of the element with which the clamps are as-

sociated and the shims or wedges 31 are disposed between the head 30 and the element A or B as the case may be. Thus the rerailing elements are clamped securely in place 5 against any movement while the wheels of a car are being guided up on the rails.

In the use of this device as illustrated in the drawings, it is obvious that the car wheel which is to be guided upon the rail X needs only to have its tread raised to a position 10 where its tread will engage upon the rail X, whereas on the opposite side of the track, the wheel on that side must be lifted to a position where its flange will ride over the 15 wheel Y.

When the car is being guided up on to the rails, the wheel on the left hand side of the car will run up the corresponding run-way or guide-way 23 and on to the face 10, the 20 flange of the wheel being guided off on to the portion 11 and in doing so, of course, the shim of the flange will run on the portion 11 and the tread of the wheel will come on to the tread face of the rail X. On the opposite 25 side of the track, however, the flange of the wheel will ride upon the guideway while the tread of the wheel will ride upon the upper face defined by the shoulder 15 while the flange rides up the inclined face 17 on to the 30 face 16 and this will bring the flange level with the upper surface of the rail so that thus the flange can roll right against this upper surface of the rail.

By providing a pair of these "rerailers" 35 for each pair of wheels or for each truck, the wheels of the car may be readily guided into place on the rails from practically any angle. It will be seen that the guideways 23 are capable of a slight lateral motion relative 40 to the elements A and B, the purpose of this lateral motion being to automatically guide the wheels of the derailed train on to the elements A and B. Under normal circumstances, each of the elements A and B will be 45 about thirty-six inches long and have a height equal to the height of the rail and the bridges or guideways 23 will ordinarily be about eight inches wide by about twenty inches long. All of the parts are to be made of steel.

50 It will be understood that the said guideway will widen out so that the intake will be about twenty inches wide.

I claim:—

1. Means for rerailing car wheels comprising an element adapted to be disposed lengthwise of a rail and having a substantially straight lateral face adapted to bear against and less in height than the side of a rail, the element being so formed from one end to its 55 middle as to receive a flange of a car wheel and guide the flange of the wheel laterally toward the rail with its tread disposed on a level with the rail, the element being so formed from its other end to its middle as to engage and raise the tread 60

of a wheel, bringing the flange thereof level with the upper face of the rail and engage the flange to force the wheel laterally to permit the flange to roll over the upper face of the rail.

2. Means for rerailing car wheels comprising an element adapted to be disposed lengthwise of and against a rail, said element having a substantially straight lateral face adapted to bear against but being less in height than the side face of the rail, the element being so formed from one end to its middle as to receive a flange of a car wheel and guide the flange of the wheel laterally toward the rail with its tread disposed on a level with the rail, the element being so formed from its other end to its middle as to engage and raise the tread of a wheel, bringing the flange thereof level with the upper face of the rail and engage the flange to force the wheel laterally to permit the flange to roll over the upper face of the rail, and a detachable guideway member disposable at either end of the element and having detachable engagement therewith.

3. Means for rerailing car wheels comprising an element adapted to be disposed lengthwise of and against a rail, the element having a substantially straight lateral face adapted to bear against but being less in height than the side of a rail, the element being so formed from one end to its middle as to receive a flange of a car wheel and guide the flange of the wheel laterally toward the rail with its tread disposed on a level with the rail, the element being so formed from its other end to its middle as to engage and raise the tread of a wheel, bringing the flange thereof level with the upper face of the rail and engage the flange to force the wheel laterally to permit the flange to roll over the upper face of the rail, and a detachable guideway member disposable at either end of the element, the opposite ends of the element being cut away to permit the inner end of 100 the guide-way to rest upon the upper face of this cut-away portion, the guide-way member and the element at opposite ends being formed one with recesses and the other with tenons to engage in said recesses, the recesses 105 being larger than the tenons whereby to permit the guide-way member to be swung laterally.

4. Means for rerailing car wheels comprising an element adapted to be disposed lengthwise of and against a rail, the element being so formed from one end to its middle as to receive a flange of a car wheel and guide the flange of the wheel laterally toward the rail with its tread disposed on a level with the rail, the element being so formed from its other end to its middle as to engage and raise the tread of a wheel, bringing the flange thereof level with the upper face of the rail, and engage the flange 115

to force the wheel laterally to permit the flange to roll over the upper face of the rail, and a detachable guide-way member disposable at either end of the element and having
5 detachable engagement therewith, the other face of the guideway member being formed with a plurality of convergent channels, that end of the guide-way member remote from the element being wider than the end engaged with the element.

10 5. Means for rerailing car wheels comprising an element adapted to be disposed lengthwise of and against a rail, the element having its upper surface formed to provide
15 a narrow rail adjoining face, defined at its middle by a vertical shoulder, the shoulder defining one edge of the face which merges toward its ends into the first named face, the outer edge of the second named face being defined by a shoulder extending laterally
20 inward from the opposite ends of the element, the shoulder defining two upwardly and inwardly inclined faces, one of said faces having thereon a shoulder extending at an
25 inward inclination from one end of the element to the middle thereof and defining an inner face adapted to receive the tread of a wheel and thereby lift the wheel as it rolls upward on the face to a position where the
30 flange of the wheel will be level with or above the head of a rail.

35 6. Means for rerailing car wheels comprising an element adapted to be disposed lengthwise of and against a rail, the element having its upper surface formed to provide a narrow rail adjoining face, defined at its middle by a vertical shoulder, the shoulder defining one edge of the face which merges toward its ends into the first named face,
40 the outer edge of the second named face being defined by a shoulder extending laterally inward from the opposite ends of the element, the shoulder defining two upwardly and inwardly inclined faces, one of said faces having thereon a shoulder extending at an
45 inward inclination from one end of the element to the middle thereof and defining an inner face adapted to receive the tread of a wheel and thereby lift the wheel as it rolls upward on the face to a position where the
50 flange of the wheel will be level with or above the head of a rail, and a detachable guideway member having one end adapted to be detachably engaged with either end of the
55 element, the opposite end of the guideway member being wider than the first named end, the upper face of the guide-way element having a plurality of guide-way channels.

In testimony whereof I hereunto affix my
60 signature.
